UNITED STATES PATENT OFFICE.

CORNELIUS F. DOUGHERTY, OF KENNEDY, CALIFORNIA.

PROTECTING-THIMBLE FOR FUME-BAGS.

1,178,385.

Specification of Letters Patent.

Patented Apr. 4, 1916.

Application filed January 27, 1916. Serial No. 74,683.

To all whom it may concern:

Be it known that I, CORMELIUS F. DOUGHERTY, a citizen of the United States, residing at Kennett, in the county of Shasta and State of California, have invented certain new and useful Improvements in Protecting-Thimbles for Fume-Bags; and I do declare the following to be a full, clear, and exact description of the invention, such as will enable others skilled in the art to which it appertains to make and use the same.

This invention relates to improvements in devices used for conducting the gases and fumes given off from metallurgical furnaces, and has for its principal object to provide an article which will greatly lengthen the life of the fume bags used in this art.

In smelting operations the fumes are conveyed from the furnaces to bags which are suspended in the bag-house for separating the solid particles contained in the fumes from the gas which escapes through the mesh of the bags. These solid particles adhere to the interior of the bags which are periodically shaken to remove the dust which falls into suitable receptacles below the same. These bags are made of wool and the chemical action of the fumes causes them after a time to rot. The part which first begins to decay is the very top end of the bag which is closed and supported by a ring in the top of the bag-house. My invention is designed to overcome this rapid decomposition of the bags at their upper ends by providing a metallic ring or thimble upon which the end of the bag is tied.

In the accompanying drawings which illustrate my invention, Figure 1 is a side elevation of the upper end of a fume bag showing the application of my invention thereto; Fig. 2 is a detail transverse section through the protector and a portion of a bag thereon; Fig. 3 is an enlarged detail transverse section showing the method of securing the hook in the upper end of the protector.

Inasmuch as the construction of a bag-house is well known to those skilled in the art, I have illustrated merely the upper end of one of the bags so as to show my invention. It is obvious that one of my improved protectors is applied to each of the bags of the bag-house. As will be seen in the drawings, my invention comprises a thimble 1 substantially the diameter of the bag B

which surrounds the same, said bag being tied by the wires or other fastening means C. In order to more readily retain the bags upon the thimbles, I provide the same with the annular grooves 2 as shown, in which the wires C are disposed.

The upper edge of the thimble 1 is bent laterally outward as shown at 3 and then downwardly as shown at 4. The top or cover for the thimble is a circular plate 5 which inclines upward slightly from its outer edge to its center and has its periphery bent downwardly as shown at 6, then inwardly as at 7, and then upwardly as at 8 to provide interlocking means for engagement with the similar means on the upper edge of the thimble. When the two parts have been engaged as shown in the drawing and soldered in this position, a gas tight joint of very strong construction is formed.

The apex of the top which is formed from the circular plate 5 is flattened as shown at 9 and provided with a central aperture 10 into which the shank 11 of a hook 12 is disposed. The shank of this hook is threaded and receives a spacing nut 13. Before placing the shank 11 into the aperture 10 a metallic washer 14 and a disk 15 are placed thereon, thus disposing the same on the top of the plate 5. After the shank has been inserted through the aperture an asbestos washer 16 is placed thereon and closely surrounds the aperture 10 and engages the inner face of the flattened portion 9. Over this asbestos washer is placed a disk 18 similar in construction to the disk 15, a metallic washer 19 being then placed on the shank and engaged with said disk 18. Finally, a clamping nut 20 is threaded on the inner end of the shank and tightly clamps the metallic washers, the disks, and the asbestos washer together, and to the flattened portion 9 of the plate so that all gas is prevented from escaping through the aperture 10. Both the disk 15 and the disk 18 have their edges turned so as to closely engage the inclined wall of the plate 5, as shown.

When the parts of this device have been assembled and the bag secured thereon, the hook is engaged with a ring R depending from the roof of a bag-house (not shown). In order to retain the hook in engagement with the ring when the bag is being shaken a wire W is disposed, as shown in the drawings, about the bill 21 of the hook in the

curved portion thereof below the ring. In order to keep the wire from slipping from the bill 21 I notch the same as shown at 22.

From the foregoing description of the construction of the device it will be seen that I have invented an extremely simple device which will effectively hold the fume bag in position and prevent very rapid decomposition of its upper end. It is also obvious that this device can be manufactured very inexpensively from sheet metal or the like and sold very cheaply.

I claim:—

1. A device of the class described comprising a thimble to be inserted in the mouth of a fume bag, said thimble having an annular groove therein to aid in securing said bag thereto, a circular plate inclined upward slightly from its outer edge toward its center, said outer edge being secured to the upper edge of said thimble, the apex of said plate being slightly flattened and provided with a central aperture, a hook having a threaded shank 15 extended through said aperture, the bill of said hook having a notch to receive a retaining wire, a spacing nut on said shank adjacent the hooked end, a disk interposed between said nut and the flattened portion 20 of the plate, said disk having its edge bent into engagement with the inclined portion of said plate, a washer between the disk and the nut, a packing washer on said shank on the inner side of said flattened portion, an additional disk disposed over said packing washer and having its edge bent into engagement with said plate, a clamping nut 25 threaded on said shank, and a clamping washer interposed between said clamping nut and the additional disk, whereby a gas tight closure is formed.

2. A device of the class described comprising a thimble to be inserted in the mouth

of a fume bag, said thimble having an annular groove therein to aid to securing the bag thereto, the upper edge of said thimble being bent laterally outward and then downwardly, a circular plate inclined upward slightly from its outer edge toward its center, said outer edge being bent downwardly, then laterally inward, and then upwardly to provide an interlocking means for engagement with the bent upper edge of said thimble, the apex of said plate being slightly flattened and provided with a central aperture, a hook having a threaded shank 30 extended through said aperture, the bill of said hook having a notch to receive a retaining wire, a spacing nut on said shank adjacent the hooked end, a disk interposed between said nut and the flattened portion 35 of the plate, said disk having its edge bent into engagement with the inclined portion of said plate, a washer between the disk and the nut, a packing washer on said shank on the inner side of said flattened portion, an additional disk disposed over said packing washer and having its edge bent into engagement with said plate, a clamping nut 40 threaded on said shank, and a clamping washer interposed between said clamping nut and the additional disk, whereby a gas tight closure is formed.

In testimony whereof I have hereunto set my hand in presence of two subscribing witnesses.

CORNELIUS F. DOUGHERTY.
